JUG

Richard L. Platte, Ann Arbor, Mich., assignor to The
Dow Chemical Company, Midland, Tex., a corporation
of Delaware

Filed Jan. 30, 1964, Ser. No. 78,427

Term of patent 14 years

(Cl. D58—5)

Fig. 5

Fig. 6

Fig. 1

Fig. 1

Fig. 2

Fig. 3

FIGURE 1 is an isometric view of a jug showing my new design;

FIGURE 2 is a side elevational view thereof;

FIGURE 3 is a top plan view thereof;

FIGURE 4 is a rear elevational view thereof;

FIGURE 5 is a front elevational view thereof; and

FIGURE 6 is a cross-sectional view thereof taken along the reference line 6—6 of FIGURE 2.

The portion of the bottom of the jug not shown is substantially flat. The side of the jug not shown in a mirror image of the side shown.

I claim:

The ornamental design for a jug, substantially as shown and described.
